CLAIM

The ornamental design for a float for supporting a beverage container holder, as shown and described.

DESCRIPTION

FIG. 1 is a perspective view of a float for supporting a beverage container holder according to the present invention;

FIG. 2 is a right side view thereof;

FIG. 3 is a left side view thereof;

FIG. 4 is a front view thereof;

FIG. 5 is a rear view thereof;

FIG. 6 is a top plan view thereof; and,

FIG. 7 is a bottom plan view thereof.

The broken lines in the drawing are for illustrative purposes only and form no part of the claimed design.
